FOOT MEASURING DEVICE

Joseph Mirti, Cleveland, Ohio

Application August 29, 1944, Serial No. 551,675

2 Claims. (Cl. 33—3)

1

This invention relates to foot measuring devices and aims to provide an improved device of this kind by which the contour of the bottom of the human foot can be readily measured and by which a corrective contour can be established or determined for use in constructing an arch support, insole, corrective pad or the like.

Another object of this invention is to provide an improved device of this character having a foot rest whose foot-engaging portion is formed, at least in part, by a resilient body adapted to be deformed for establishing and measuring a corrective contour for the foot.

A further object of the present invention is to provide a device of the character mentioned, in which the foot rest includes one or more sections movable in a direction longitudinally of the foot and one or more of such movable sections embodies means for establishing and measuring a corrective contour for the corresponding portion or portions of the foot.

Still another object of this invention is to provide an improved device of this character, having novel means by which the movable sections of the foot rest can be readily shifted the proper amount and novel means by which the resilient bodies of the respective sections can be readily deformed by controlled amounts or increments for establishing the corrective contour.

Yet another object of the invention is to provide an improved device of this kind in which an elastic covering extending over and confining the deformable resilient body gives the foot rest a smooth surface and is adapted to be distended by the deformation of the resilient body.

The invention can be further briefly summarized as consisting in certain novel combinations and arrangements of parts hereinafter described and particularly set out in the appended claims.

In the accompanying sheets of drawings

Fig. 1 is a perspective view of a foot measuring device constructed according to the present invention.

Fig. 2 is a side elevation of the device.

Fig. 3 is a partial top plan view of the device.

Fig. 4 is a transverse sectional view taken on line 4—4 of Fig. 1 and showing the means for shifting one of the movable sections of the foot rest.

Fig. 5 is a partial longitudinal sectional view taken on line 5—5 of Fig. 4; and

Fig. 6 is another transverse sectional view taken on line 6—6 of Fig. 1.

For the purpose of describing the invention in greater detail further reference will now be made

2

to the accompanying drawings in which one embodiment of the improved foot measuring device is illustrated. As shown in the drawings the device comprises, in general, an elongated base 10 and a foot rest 11 supported by the base and extending longitudinally thereof. The foot rest 11 is of a sectional construction and may embody any desired number of parts or sections, but in this instance, comprises three sections which include a heel section 12, an intermediate or instep section 13 and a front or toe section 14. One or more of the sections of the foot rest, in this case the two sections 13 and 14, are movable longitudinally of the base as is further explained herein-after.

The base 10 comprises an elongated slab or body 10a having a substantially flat bottom upon which the device may rest or stand, and a pair of laterally spaced longitudinally extending side rails 15 and 16. The side rails 15 and 16 are attached to the body 10a of the base and extend thereabove so as to define a longitudinally extending opening or guide-way 17 along which the movable sections 13 and 14 of the foot rest can be shifted. The side rails 15 and 16 include relatively narrower spacing strips 15a and 16a so that the guide-way 17 will have undercut grooves or lateral extensions 17a to which further reference will be made hereinafter.

The heel section 12 of the sectional foot rest 11 is a stationary section which is secured in the guide-way 17 and forms a support for the heel of a human foot when the latter is placed on the foot rest. The heel section 12 may be constructed from a block of wood, a body of molded plastic material or from any other suitable substance and is provided with an appropriately dished or contoured upper surface which will conform generally to the shape and contour of the underside of the heel of the foot for comfortably supporting the same. An upstanding stationary abutment member 19 is provided immediately at the rear of the heel support 12 and is adapted to be engaged by the back of the heel for properly locating the foot on the foot rest 11. This abutment is provided with a concave heel engaging surface or portion 19a which is of a size and shape to comfortably and accurately engage the back of the heel when the foot is placed on the foot rest. The abutment 19 can be constructed of wood or other suitable material and is suitably secured in the guide-way 17 of the base 10. The heel section 12 and the abutment 19 can be covered with a layer of leather or suitable finishing material.

The movable sections 13 and 14 of the foot rest 11 each comprise a body portion 21 and a top or table portion 22. The body 21 comprises a block formed of wood or other appropriate material which is slidable longitudinally in the guide-way 17 and is provided with lateral extensions or flanges 23 which are operable in the undercut grooves 17a for retaining the sections in the guide-way. The top or table portion 22 comprises a plate or contour member 24 and a covering of elastic sheet material 25 extending thereover. The member 24 may comprise a sheet or slab of leather, or other appropriate material, whose upper surface is shaped to conform generally to the contour of the underside of the foot. In the case of the intermediate or instep section 13, which engages and conforms with the transverse arch or instep portion of the foot, the top or table portion 22 has a surface which slopes or tapers transversely of the foot rest 11 and is convexly curved longitudinally of the foot rest. In the case of the front or toe section 14 which receives and supports the forward portion of the foot including the longitudinal arch thereof, the top or table portion 22 has a surface of varying curvature including both concave and convex portions and corresponding generally with the contour and shape of the underside of the portion of the foot extending forwardly of the instep.

As shown in Figs. 4 and 6 of the drawings, the plate member 24 is connected with the body portion 21 by suitable fastening members, such as the nails 26 extending therethrough, and extends laterally beyond the edges of the guide-way 17 into overlying relation to the side rails 15 and 16. The elastic covering 25 extends over and around the edges of the plate member 24 so that the edges of the covering material will be concealed and so that the covering material will provide the top of the foot rest with a smooth foot-engaging surface as well as a neat and attractive appearance. The covering 25 can be formed of a soft stretchable leather, a soft sheet rubber or any other appropriate elastic sheet material. This covering material can be cemented or otherwise suitably attached to the plate member 24 on which it also forms a smooth and attractive finish.

An important feature of the present invention is that one or more of the sections of the foot rest 11 are provided with a non-metallic resilient deformable body which forms a part of the foot-engaging top or plate 22 of these sections and which can be deformed or distorted for the purpose of establishing and determining a corrective contour for corresponding portions of the foot which is placed on the foot rest. In the drawings I show the intermediate section 13 of the foot rest provided with such a deformable body 28 and I also show the section 14 provided with a similar deformable body 29. These deformable bodies 28 and 29 are preferably in the form of oval or elliptical pads recessed into the tops or plate members 22 of these sections and may be constructed of soft rubber or any other suitable material which is soft, resilient and pliable. In the section 13 the resilient body or pad 28 is of a size and shape and is located such that it can be used for measuring or determining the location, shape and thickness of a corrective pad or support for the transverse arch of the foot. The resilient body or pad 29 embodied in the section 14 is of a size and shape and is located on this section such that it can be used for determining the location, shape and thickness of a corrective pad or arch support for the

longitudinal arch of the foot. The corrective pad or support corresponding with the deformable body 29 of the section 14 is sometimes referred to as a metatarsal pad.

The plate members 24 of the sections 13 and 14 are provided, respectively, with recesses or openings 31 (see Figs. 5 and 6) in which the deformable bodies 28 and 29 are located. These openings may be of a somewhat oval or elliptical shape corresponding with the shape of the deformable bodies 28 and 29 and preferably have beveled or sloping edges. The deformable bodies have a rounded top or contour with a maximum thickness at or adjacent their center and taper in thickness to a relatively thin sharp edge 32 extending around their periphery. The bodies 28 and 29 are retained in the recesses 31 by the elastic covering 25 extending thereover, although if desired, an intermediate elastic layer 33 or covering may be used to assist the covering 25 in confining these deformable bodies. The intermediate elastic layer 33 may be a sheet of soft rubber or other suitable elastic material. Although Figs. 5 and 6 show only the body 29, it will be understood, of course, that the deformable body 28 is mounted and retained in a corresponding recess or opening of the section 13.

In making use of the deformable bodies 28 and 29 of the sections 13 and 14 of the foot support, I provide each of these sections with means by which such deformable body can be distorted or deformed so as to define or establish a corrective contour for the corresponding portion of the foot. Since this deforming means is of a similar or identical construction for both of the sections 13 and 14 it will be described in detail only in connection with the deformable body 29. As shown in the drawing, this deforming means includes a plunger 35 which is slidable in an upright guide tube 36 and has its upper end located adjacent to or in engagement with the deformable body 29. If desired, the body 29 can be attached to the upper end of the plunger 35 as by means of a headed fastening member 37 extending through such body.

The guide tube 36 is carried by the section 14 and is mounted in a suitable opening provided in the body portion 21 of this member. The base 10 of the device is provided with a longitudinally extending clearance recess or slot 38 which accommodates the portion of the guide tube which extends in depending relation below the body portion 21. The plunger 35 is provided with a rack 39 with which a pinion 40 cooperates. The pinion 40 is carried by a transverse shaft 41 supported in laterally aligned bearings 42 and 43 which are mounted in suitable openings of the body portion 21 and extend laterally outwardly into clearance slots 44 and 45 of the side rails 15 and 16. The bearings 42 and 43 are preferably of a square or non-circular cross-section which, in the case of the bearing 43, accomplishes an additional function as will be explained hereinafter. The bearings 42 and 43 are carried by the body 21 and are slidable in the slots 44 and 45 during movement of the section 14 longitudinally in the guide-way 17 of the base 10.

The pinion shaft 41 is provided at one end thereof with a shouldered retaining nut or cap 47 and at its other end with an actuating knob 48 which is connected therewith by means of a transverse pin 49. When the knob 48 is rotated to drive the shaft 41 in a direction to cause the pinion 40 to lift the rack 39, the plunger 35 is pushed 75 upwardly against the underside of the deformable

body 29 causing the latter to be deformed or distorted upwardly to a bowed condition in which it causes the elastic coverings 25 and 33 to be stretched and distended. The confining effect of the elastic coverings 25 and 33 assists the plunger 35 in deforming the resilient body 29 to such an upwardly bowed condition and permits this to be carried out in a manner such that, although the contour of the foot-receiving surface of the section 14 is altered, the convex contour or curvature of the altered portion will still merge smoothly with the surrounding portions of the top or plate portion of the section without producing wrinkles or irregularities which would be uncomfortable to the foot.

The elastic coverings 25 provided on the movable sections 13 and 14 are cemented thereto as mentioned above and, as shown in the drawings, have their outer perimeters anchored continuously therealong on the plate members 24 by having their edge portions extending around and under the edges of these plate members. The portions of the coverings 25 which overlie the deformable pads 28 and 29 are not anchored to the plate members 24 and hence are capable of being distended and stretched upwardly by these pads, as just explained above. Since the coverings 25 are anchored continuously along their perimeters, the portions which overlie the pads 28 and 29 will be stretched upwardly by the latter to a distended shape, which is bowed both transversely and longitudinally of the device.

The deformable body 29 is deformed or distorted by the means just described to an extent necessary to produce a corrective contour on the foot rest 11 as may be needed by the particular foot being analyzed. This is determined by a skilled operator or diagnostician who uses the device and actuates the knob 48. To permit this deforming of the body 29 to be carried out gradually and by small increments in a step by step manner which will permit repeated checking with the patron or patient whose foot is being analyzed, I provide a ratchet means for the knob 48.

This ratchet means comprises an annular series of teeth 51 and a beveled lug 52 carried by the knob 48 and cooperating with such ratchet teeth. The teeth 51 are carried by a disc-like head or enlargement 53 provided on the outer end of the bearing 43 and which is held against rotation by the non-circular cross-sectional shape of the bearing. A compression spring 54 located in a recess of the knob 48 and disposed around the outer end of the pinion shaft 41 urges the knob axially of the shaft in a direction to cause engagement of the lug 52 with the ratchet teeth 51.

When the knob 48 is rotated in a direction to lift the plunger 35 as above explained, the lug 52 rides over the ratchet teeth 51 in succession and as the lug passes over each successive tooth it holds or locks the deforming means so as to retain the body 29 in the deformed condition corresponding with the extent of angular movement through which the knob has been rotated. When the deformation of the resilient body 29 is to be decreased or when this body is to be restored to its initial or released condition, the knob 48 is withdrawn axially of the pinion shaft 41 against the action of the spring 54 to thereby disengage the lug 52 from the ratchet teeth 51 and permit reverse rotation of the knob.

To enable the operator of the device to know to what extent the resilient body 29 has been deformed and to make a record of such deformation, I provide indicating means adjacent the knob

48 comprising a pointer 55 carried by the knob and a stationary dial 56 supported by the non-circular bearing 43 and carrying suitable indications or graduations 56a.

- 5 As mentioned above, the sections 13 and 14 of the foot rest 11 are shiftable longitudinally along the guide-way 17 of the base 10 and relative to the heel support 12. Such movement of the sections 13 and 14 permits them to be adjusted to 10 suit the length or size of the foot being analyzed. By adjusting the intermediate section 13 in this manner it can be properly located with respect to the instep or transverse arch of the foot so that the corrective contour can be established by 15 means of the deformable body 28 in the manner above explained. Likewise, the adjustment for the movable section 14 permits this section to be adjusted to a position which will locate the deformable body 29 in proper relation to the longitudinal arch of the foot so that this deformable body can be used in establishing and determining a corrective contour for a metatarsal pad or other arch support in the manner above explained.
- 20 25 The adjustment of the movable sections 13 and 14 to the proper positions can be facilitated by the use of scales provided on the side rails 15 and 16 and pointers 59 provided on the movable sections. These scales and pointers also permit a 30 record to be made by the operator of the proper adjustments of the movable sections when such adjustments have been determined for a foot which is being analyzed.

For shifting the movable sections 13 and 14 of 35 the foot rest 11 along the guide-way 17 of the base 10 for the purpose just explained above, I provide the body 21 of each section with a rack 60 with which a pinion 61 cooperates. The pinion 61 is carried by a pinion shaft 62 which is mounted in 40 suitable bearings 63 and 64 supported by the body 10a of the base 10. An actuating knob 65 is connected with the pinion shaft 62 as by means of the pin 66 so that rotation of the knob for one or the other of the movable sections 13 and 14 45 will cause such section to be shifted along the guide-way in a direction corresponding with the direction of rotation of the knob.

Another feature embodied in this improved foot measuring device is the provision of contoured shapes at the adjacent ends of the sections 50 12, 13 and 14 of the foot rest 11 as shown in Figs. 1 and 3 and which permit these sections to have an interfitting engagement when they are adjusted to a close or abutting relation, as for example for 55 a relatively short foot. These contoured shapes include a forwardly extending convexly curved projection 67 on the forward end of the fixed section 12 and a corresponding concavely curved mating recess 68 in the rear end of the intermediate section 13. Similarly, the rear end of the section 14 has a rearwardly extending convexly curved projection 69 thereon and the forward end of the intermediate section 13 has a corresponding concavely curved mating recess 70 60 therein. As shown in Fig. 3, the deformable pad 29 may be located on the section 14 so that it extends part-way into or over the curved projection 69 of this section.

From the foregoing description and accompanying drawings it will now be readily seen that the present invention provides an improved measuring device by which a corrective contour can be readily established or determined for a foot being analyzed. It will be seen also that the use of 75 movable sections in the foot rest permits the de-

vice to be used with feet of different length, and the use of deformable resilient bodies in the movable sections permits the contour thereof to be readily altered in determining the requirements of the foot being analyzed without producing abrupt or irregular changes in the foot rest. It will be seen moreover that the measuring or analyzing operation can be carried out entirely by the manipulation of the device and does not require the actuation of any movable parts on the part of the patron or patient. It will be understood also that with the data obtained from the indicating scales of the device, properly fitting pads, arch supports, or shoes can be constructed.

While I have illustrated and described my foot measuring device in considerable detail it will be understood, of course, that I do not wish to be correspondingly limited but regard my invention as including all changes and modifications coming within the spirit of the invention and the scope of the appended claims.

Having thus described my invention, I claim:

1. In a foot measuring device, an elongated base having thereon a longitudinal guide-way and a heel abutment, a foot rest extending away from said abutment in the direction of said guide-way and including a stationary heel section and a pair of toe and instep sections which are movable along said guide-way, said toe section having foot engaging means thereon including a deformable pad on the upper side thereof and an elastic sheet covering extending over said pad and anchored continuously around its outer perimeter on said toe section, elevating means operable to lift said pad for stretching said sheet covering upwardly to a convex shape which is bowed both longitudinally and transversely of said foot rest, said instep section having foot engaging means thereon including a deformable pad on the upper side thereof and an elastic sheet covering extending over said pad and anchored continuously around its outer perimeter on said instep section, elevating means operable to lift the pad of said instep section for stretching the sheet covering thereof upwardly to a convex shape which is bowed both longitudinally and transversely of said foot rest, and means operable to shift said toe and instep sections along said guide-way, the adjacent ends of said sections having contoured projections and

recesses thereon adapted for mating engagement.

2. In a foot measuring device, an elongated base having thereon a longitudinal guide-way and a heel abutment, a foot rest extending away from said abutment in the direction of said guide-way and including a stationary heel section and a pair of toe and instep sections which are movable along said guide-way, said toe section having foot engaging means thereon including a deformable pad on the upper side thereof and an elastic sheet covering extending over said pad and anchored continuously around its outer perimeter on said toe section, elevating means operable to lift said pad for stretching said sheet covering upwardly to a convex shape which is bowed both longitudinally and transversely of said foot rest, said instep section having foot engaging means thereon including a deformable pad on the upper side thereof and an elastic sheet covering extending over said pad and anchored continuously around its outer perimeter on said instep section, elevating means operable to lift the pad of said instep section for stretching the sheet covering thereof upwardly to a convex shape which is bowed both longitudinally and transversely of said foot rest, means operable to shift said toe and instep sections along said guide-way, the adjacent ends of said sections having contoured projections and recesses thereon adapted for mating engagement, and ratchet means embodied in the elevating means of said toe and instep sections by which the lifting of the deformable pads thereof is accomplished in step-by-step increments.

JOSEPH MIRTI.
